UNITED STATES PATENT OFFICE.

WILLIAM JAMES BULGIN, OF WORCESTER, ENGLAND, ASSIGNOR TO HEENAN & FROUDE LIMITED, OF MANCHESTER AND WORCESTER, ENGLAND.

TOP-FEED DOOR FOR REFUSE DESTRUCTORS AND OTHER FURNACES.

Application filed November 7, 1925. Serial No. 67,695.

This invention relates to improvements in mechanically operated top feed doors for refuse destructors and other furnaces of the type in which the operating means first cause 5 the door to be raised from its seating and then moves the door horizontally from over the opening into the furnace.

The present invention consists in the combination with the feed door of a supporting 10 frame, the feed door being capable of vertical movement in relation thereto, a feeding chute or tundish carried by the supporting frame, and means for giving a lifting movement to the door followed by a longitudinal 15 movement of the whole device.

The invention will be described with reference to the accompanying drawings in which:—

Fig. 1 is a longitudinal section through the 20 door and operating means.

Fig. 2 is a plan of same.

Fig. 3 is a transverse section on line 3—3

Fig. 2.

Fig. 4 is a detail view of the crank for 25 raising the door from its seating.

Fig. 5 is a detail view of one of the slotted lugs from which the door is suspended.

The door A and the tundish or chute B, which is moved into position over the opening C into the furnace when the door A is removed therefrom, are both carried by a single framing D. The framing D is provided with two pairs of lugs d¹ which rest on the shafts E E¹ on which are loosely mounted wheels e e¹ running on the rails or runways F².

The door A is suspended from the shaft E by a pair of slotted lugs a¹ each formed with a semi-cylindrical projecting portion a² the flat face of which is adapted to be engaged by a correspondingly shaped portion f on a sleeve F keyed on the shaft E. The sleeve F at one end of the shaft E forms the end of a depending lever or rod F¹ forked at its lower 45 end f¹.

A depending lever G is mounted on a shaft E¹ adjacent to one of the wheels e¹ and the lever G is connected to the corresponding lever or rod F¹ by a connecting rod 50 g so that any rotary movement imparted to the shaft E is communicated to the lever F¹.

A link h is affixed to the shaft E¹ and is connected to a horizontal link H the free end of which is adapted to be engaged by the end of a ram K operated by compressed air, steam or other fluid pressure so that when the ram K moves outwards from its cylinder k the links h and H will be moved to rotate the shaft E¹. The motion of the link H is limited to the ram coming into contact with the bracket H¹ fixed to the frame-work so that further movement of the ram pushes the whole of the loose frame-work and chute bodily forwards.

The charging door A which is preferably 65 lined with firebrick although suspended from the shaft E is separated from the framing D and the chute or tundish B and can be raised from and lowered on to its seating without movement being imparted to the 70 framing and the chute or tundish.

In operation when it is desired to feed a fresh charge into the furnace the ram K is operated and moves forward rotating the 75 shaft E¹ through the links h and H. The rotation of the shaft is imparted to the lever or arm F¹ the shaft E and the sleeves F the face of which engages with the part a² of the corresponding lugs a¹ causing the door to be raised from its seating. The further 80 movement of the ram K engages the bracket H¹ and moves forward the whole of the framing, door and chute or tundish, to remove the door from over the furnace opening and bring the chute or tundish in position over the opening.

After the charge has been fed into the furnace the reverse series of operations take place, the framing, door and chute or runway being first moved into the original position and the door then lowered on to its seating.

What I claim as my invention and desire to protect by Letters Patent is:—

In combination with a top feed door of an 95 incinerator or like furnace, a supporting frame for said door, means connecting said door to the said frame and permitting vertical movement of said door relative to said frame, a feed chute carried by said frame 100 and moving longitudinally therewith to occupy the position of said door when the

latter is moved from its closure position, shafts supporting said door and framing, wheels loosely mounted on said shafts, levers and connecting rods, connecting said shafts together, a link carried by one shaft, a fluid actuated ram adapted to engage said link to rotate said shafts, and a bracket affixed to

the framing adapted to be engaged by said ram after the latter has moved a predetermined amount to move the whole device longitudinally. 10

In testimony whereof I have hereunto set my hand.

WILLIAM JAMES BULGIN.
